UNITED STATES PATENT OFFICE.

LUTHER D. LOVEKIN, OF PHILADELPHIA, PENNSYLVANIA.

BOILER.

1,119,025.

Specification of Letters Patent.

Patented Dec. 1, 1914.

Application filed June 25, 1913. Serial No. 775,662.

To all whom it may concern:

Be it known that I, LUTHER D. LOVEKIN, a citizen of the United States of America, residing in the city and county of Philadelphia, in the State of Pennsylvania, have 5 invented certain new and useful Improvements in Boilers, of which the following is a true and exact description, reference being had to the accompanying drawings, which 10 form a part thereof.

My present invention relates to steam generating boilers, and has for its object to provide a horizontal cylindrical boiler, such as the Scotch type of marine boiler, with 15 suitable internal provisions for drying and superheating the steam issuing from the boiler.

In the practical use of marine boilers of the Scotch type and other horizontal cylindrical boilers, as heretofore constructed, the steam issuing from the boiler frequently contains as high as five per cent. of moisture, and with this type of boiler the issuing 20 steam is regarded as "commercially dry" 25 when it contains as little as two and one-half per cent. of moisture. The reason for this high percentage of moisture in steam issuing from a boiler of the kind referred to is due to the violent ebullition set up in 30 the neighborhood of the combustion chamber and the hotter parts of the boiler tubes, which causes bubbles of steam to rise with such rapidity as to keep the water surface continually broken. These bubbles of steam 35 carry up with them from the broken water surface small particles of water which are held in mechanical suspension in the steam. Steam containing as much as two and one-half per cent. of moisture should not be 40 used in engine cylinders or turbines, and moisture present in appreciably smaller percentages produces water hammering and other troubles, and is a frequent source of considerable damage. Heretofore it has 45 been frequently proposed to provide some sort of steam separator within the boiler to reduce the amount of moisture carried by the steam leaving the boiler, but these separating devices whether in the form of the common dry pipe perforated on top, or in more complex form, are all open to the objection that they tend to lower the pressure at which 50 the steam leaves the boiler and in practice are not effective in securing the delivery of dry steam. It is possible, of course, to dry 55 and to superheat the steam by means of ex-

ternal drying and superheating devices, and this practice is generally followed, but such external devices are cumbersome and more or less expensive, and generally inefficient 60 and undesirable.

In constructing a boiler in accordance with the present invention, I place a series of heating tubes within the boiler shell above the water level and extending between the end walls thereof, and pass a portion of the products of combustion through these tubes, and I so arrange the boiler that the steam issuing therefrom will pass through the spaces between these tubes under such conditions that it will be effectively dried. When the tubes are properly arranged and proportioned and suitable provisions are made for directing the flow of the steam relative to the flow of the hot 70 gases in the tubes, as hereinafter explained in detail, I can give the steam from fifty to one hundred degrees of superheat when this is desirable.

The various novel features of construction 80 and arrangement which characterize my invention are pointed out with particularity in the claims annexed to and forming a part of this specification. For a better understanding of the invention, however, and of 85 the advantages possessed by it, reference should be had to the accompanying drawings and descriptive matter, in which I have illustrated and described forms in which my invention may be embodied.

Of the drawings: Figure 1 is a sectional elevation of one form of boiler constructed in accordance with the present invention, the section being taken on the line 1—1 of Fig. 2; Fig. 2 is a section taken partly on 95 the line 2—2, and partly on the line 2^A—2^A of Fig. 1; Fig. 3 is a sectional elevation taken similarly to Fig. 1 showing a portion of a slightly different construction; Fig. 4 is a section on the line 4—4 of Fig. 3; Fig. 100 5 is a partial sectional elevation of a third form of boiler constructed in accordance with the present invention; Fig. 6 is a sectional elevation of a boiler of the return tubular type equipped with my invention; 105 and Fig. 7 is a sectional elevation of a boiler of the locomotive type equipped with my invention.

In the drawings, and referring first to the construction shown in Figs. 1 and 2, A represents the wall of the cylindrical boiler shell, and B and C the front and rear end

walls, respectively. Within the boiler shell and separated from the front and rear ends thereof though much nearer the latter than the former are located the usual combustion 5 chamber, or chambers. As shown in Figs. 1 and 2, there are three of these chambers, one central chamber E, and two side chambers E'. Those familiar with this type of boiler will understand, however, that the number 10 of combustion chambers provided depends upon the operating condition and to the size and to some extent the preferences of the boiler. The front end wall B of the boiler shell and the front end of each of the combustion chambers E and E' are connected 15 by the wall of a corresponding tubular furnace chamber D. The wall of each of the furnace chambers D is in the form of a corrugated cylinder. Above and at the sides 20 of each of the furnace chambers D are return flues F which extend between the front ends of the combustion chambers and the front end wall B of the boiler. The flues F serve to convey products of combustion 25 which enter the combustion chambers E and E' from the furnace chambers D to the smoke box Q into which the flues F discharge at the front end of the boiler. The construction shown in Figs. 1 and 2 as hereinbefore described in detail possesses nothing 30 now novel with me, but on the contrary is a typical example of a marine boiler of the Scotch type.

Each of the combustion chambers E and 35 E' is connected at its upper end to a chamber formed in a casing M attached to the rear end of the boiler proper by a number of short tubes L which extend between the rear end walls of the combustion chambers 40 and the rear end wall C of the boiler. The hot gases passing from the combustion chamber into the casing M are conveyed from the latter to the smoke box Q through a group of tubes P which extend through the interior 45 of the boiler between the end walls B and C near the top of the boiler shell. The casing M which may be formed of sheet iron lined with refractory material is preferably formed with clean out doors M' and 50 M''. Preferably also a damper M''' is provided by which the flow of hot gases through the casing may be regulated and cut off. O represents stay bolts connecting the end walls B and C of the boiler below the level 55 of the tubes P and above the level of the combustion chamber. As shown, the casing M is shaped to provide an air space N, open to the atmosphere at its ends, into which the rear ends of the stay bolts O project and are 60 thereby protected from the high temperature prevailing within the casing M. It is to be noted that the tubes P perform the purpose of and take the place of stay bolts similar to the bolts O which otherwise would 65 have to be employed to tie the upper por-

tions of the end walls B and C together. Similarly the short tubes L take the place of stay bolts such as the stay bolts O beneath them which would otherwise be required to tie the rear end walls of the combustion 70 chamber to the rear end wall of the boiler proper. The tubes P are preferably arranged in staggered rows and sufficiently close together so that the steam in traversing the tubes P is compelled to follow a tortuous path which will tend to cause the particles of moisture carried by the steam to impinge against the hot tubes P. Advantageously, also, provisions are made for compelling the steam to pass along the tubes P 75 for a considerable distance and to traverse the tubes several times before reaching the steam outlet R which opens from the top of the boiler near the rear end of the latter in this construction. As shown in Figs. 1 and 80 2 these provisions comprise a baffle wall S which extends beneath the tubes from the rear end wall of the boiler to a point adjacent the front end wall of the boiler and is attached at its side edges to the boiler wall 85 at opposite sides of the tubes P. Transverse baffle walls S', S'', T and T' operate in conjunction with the baffle S to compel steam to more or less completely traverse the tubes P 90 several times on its way to the outlet R as 95 well as to pass along side of and in close proximity to the tubes P for a distance equal to considerably more than half the length of the boiler. Furthermore, the flow of the steam longitudinally of the tubes is opposite 100 in direction to the flow of the hot gases within the tubes. The counter current flow of the hot gases and steam thus obtained is of great importance in obtaining not only a high degree of superheat but also a steady superheating effect. As the steam passes along 105 and across the tubes P on its way to the outlet R it is thoroughly dried and may be more or less superheated. The extent of superheat imparted to the steam will of course 110 depend upon the number, size and arrangement of the tubes P, and the volume and temperature of the hot gases passing through the pipes P. The degree of superheat attained may be regulated by manipulating 115 the damper M''. The location of the inlet to the superheating space above the baffle wall S at the opposite end of the boiler from that at which the combustion chamber is located 120 is advantageous in that it increases the distance to the steam outlet traveled by the steam rising in the vicinity of the combustion chamber where ebullition is the most violent and the most water is carried up with the steam. While the portion of the 125 baffle S beneath the tubes P terminates at some distance from the left hand end of the boiler as seen in Fig. 1, the portions S' of the baffle at the sides of the tubes P preferably extend from one end of the boiler to the 130

other. They thus serve to prevent water running up the sides of the boiler shell into and above the tubes P, as it tends to do both from the ebullition effects within the boiler and the bodily movements of the boiler, when used on ships for instance.

The construction shown in Figs. 3 and 4 differs from that shown in Figs. 1 and 2 only in the location of the steam outlet and

- 10 in the omission of the special provisions of Figs. 1 and 2 for directing the flow of the steam across and along the tubes P. As shown in Figs. 3 and 4 the steam outlet RA is located at the end of the boiler remote 15 from the combustion chamber to increase the travel of the wettest steam which arises in the vicinity of the combustion chamber. This portion of the steam will naturally pass for a considerable portion of its travel 20 in the boiler lengthwise of and in the spaces between the tubes P. Baffles Z in the form of flanged bars attached to the boiler shell are located at the sides of the tubes to prevent water from running up the sides 25 of the boiler shell into and above the tubes P. A fairly satisfactory steam drying effect may be obtained with the construction shown in Figs. 3 and 4 but the superheating effect is much less satisfactory than that 30 of the construction shown in Figs. 1 and 2.

In Fig. 5 I have shown my improved steam drying and superheating provisions applied to a boiler of what may be called the combined Scotch and gunboat type, differing from that shown in Figs. 1 to 4 in that the combustion chamber EA or each of them if there be more than one is not only connected to the front end of the boiler by one or more furnace chambers D and return 35 flues F, but is also connected to the rear end of the boiler by direct flues G which are shorter and smaller in diameter than the flues F and discharge into a smoke box QA connected to the rear end of the boiler. The 40 smoke box QA and the smoke box Q may well be connected to the same chimney or draft pipe. In Fig. 5 the combustion chamber EA or each of them if there be more than one is connected adjacent its upper end 45 by tubes LA to a chambered casing MA. The tubes LA and casing MA correspond generally to the tubes L and chamber M of the construction first described. The tubes P leading from the chamber MA to the 50 front smoke box Q perform the same function as in the construction first described, and the boiler shown in Fig. 5 comprises 55 baffle and guide provisions S, S', T and T' similar to those shown in Figs. 1 and 2.

60 My improved means for drying and superheating steam are applicable, of course, to other types of horizontal cylindrical boilers than those of the Scotch and gunboat types, in which internal combustion and furnace 65 chambers are employed, and in Fig. 6 I

have illustrated the use of my invention in connection with an externally fired boiler of the return tubular type. As shown in Fig. 6, the boiler shell AA has the usual submerged return flues F' connected between 70 the end walls of the boiler shell and serving to convey the products of combustion passing from the external furnace chamber DA through the external combustion chamber D¹⁰ and the extension D¹¹ thereof, at the 75 rear end of the boiler, to the smoke box QB at the front end of the boiler. A portion of the products of combustion pass from the combustion chamber extension D¹¹ through the perforated baffle D¹² into the auxiliary chamber D¹³ from which they pass 80 to the smoke box QB through the drying and superheating tubes P' which extend between the end walls of the boiler shell and are located above the water level. In conjunction with these tubes I employ baffles SA, S', S², T and T' analogous in arrangement to the baffling shown in Fig. 1 for causing the steam issuing from the boiler to 85 traverse and flow along the tubes P' in a direction counter to the flow of the hot gases through those tubes. In this construction the steam outlet RB leads from the top of the boiler shell adjacent the rear end of the boiler and steam enters the space above 90 the baffle SA adjacent the front end of the boiler.

In Fig. 7 I have illustrated the application of my invention to a boiler of the locomotive type. As shown in Fig. 7, the combined furnace and combustion chamber EB located within the cylindrical boiler shell AB and the usual downward extension A¹⁰ of the boiler shell at one end of the latter is connected by the submerged flues F² to 105 the smoke box QC at the opposite end of the boiler. The drying and superheating tubes P² extend between the end walls of the boiler above the water level and connect the smoke box QC to a chambered casing 110 MB at the opposite end of the boiler. The latter receives a portion of the hot gases from the chamber EB through the short tubes LB. In conjunction with the tubes P², baffles SA, S', S², T and T' are employed 115 as in Fig. 6, but in this construction the steam outlet RC is located at the same end of the boiler as the furnace and combustion chamber EB, and steam enters the space above the baffle SA at the end of the boiler 120 at which the smoke box is arranged.

In all of the forms of the invention shown by the drawings, except that shown in Figs. 3 and 4, it will be observed that the arrangement of the baffling and the steam outlet is 125 such that a steam drying and superheating space is provided within the boiler shell which communicates with the steam generating portion proper of the interior of the boiler at a point at which the ebullition is 130

the least violent and through which the steam flows in a direction counter to the flow of the hot gases in the tubes passing through this space. This arrangement is highly effective in securing steam which is not only dry but has a high and fairly definite degree of superheat.

Certain general features of construction and arrangement which are novel with me and are disclosed in common herein and in my copending application, Serial No. 808,569, filed December 24, 1913, but not generically claimed herein, are so claimed in my said application Serial No. 808,569.

While in accordance with the provisions of the statutes, I have illustrated and described the best forms of my invention now known to me, it will be apparent to those skilled in the art that changes may be made in the form of the apparatus disclosed without departing from the spirit of my invention, and that under some conditions certain features of my invention may be used without a corresponding use of other features.

Having now described my invention, what I claim as new and desire to secure by Letters Patent, is:

1. In a horizontal cylindrical boiler, the combination with the boiler shell having a steam outlet and the usual submerged heating flues and other submerged heating surfaces, of a set of tubes located within the boiler shell above the water level therein and extending from one end of the boiler to the other, a baffle arranged within the boiler shell above the water level and below said tubes and steam outlet to provide a steam space above the baffle which is in free communication with the steam generating space beneath the baffle only at a substantial horizontal distance from said steam outlet, and provisions for passing hot gases through said tubes.

2. In a horizontal cylindrical boiler, the combination with the boiler shell having a steam outlet adjacent one end and the usual submerged heating flues and other submerged heating surfaces, of a set of tubes located within the boiler shell above the water level therein and extending from one end of the boiler to the other, a baffle arranged within the boiler shell above the water level and below said tubes and steam outlet to provide a steam space above the baffle freely communicating with the steam generating space beneath the baffle only at the end of the boiler remote from said steam outlet, and provisions for passing hot gases through said tubes in a direction counter to the general direction of steam flow through said steam space toward said steam outlet.

3. In a horizontal cylindrical boiler, the combination with the boiler shell having a steam outlet adjacent one end and the usual

submerged heating flues and other submerged heating surfaces, of a set of tubes located within the boiler shell above the water level therein and extending from one end of the boiler to the other, a baffle arranged within the boiler shell above the water level and below said tubes and steam outlet to provide a steam space above the baffle freely communicating with the steam generating space beneath the baffle only at the end of the boiler remote from said steam outlet, other baffle provisions for causing the steam to traverse said tubes as it flows through said steam space to said steam outlet, and provisions for passing hot gases through said tubes in a direction counter to the general direction of steam flow through said steam space toward said steam outlet.

4. The combination in a horizontal cylindrical boiler comprising an external boiler shell, an internal combustion chamber located at a distance from one end wall of the boiler and the usual submerged flues leading from said combustion chamber to said one end wall and to the other end wall of the boiler, and having a steam outlet adjacent said other end wall, of tubes located within said boiler shell above the water level in the boiler and extending between said end walls, means for causing hot gases discharged by said flues at said other end of the boiler to be conveyed through said tubes to said one end of the boiler, and a baffle arranged within the boiler shell above the water level and below said tubes and steam outlet to provide a steam space above the baffle freely communicating with the steam generating space beneath the baffle only at the end of the boiler remote from said steam outlet.

5. The combination in a horizontal cylindrical boiler comprising an external boiler shell, an internal combustion chamber located at a distance from one end wall of the boiler, and the usual submerged flues leading from said combustion chamber to the other end wall of the boiler, and having a steam outlet adjacent said other end wall, tubes located within said boiler shell above the water level in the boiler and extending between said end walls, means for causing hot gases discharged by said flues at one end of the boiler to be conveyed through said tubes to the opposite end of the boiler comprising a chambered casing external to the boiler shell, means for regulating the flow of hot gases through said casing, and a baffle arranged within the boiler shell above the water level and below said tubes and steam outlet to provide a steam space above the baffle freely communicating with the steam generating space beneath the baffle only at the end of the boiler remote from said steam outlet.

6. The combination in a horizontal cylindrical boiler comprising an external boiler

- shell, an internal combustion chamber located at a distance from one end wall of the boiler, and the usual submerged flues leading from said combustion chamber to the other 5 end wall of the boiler, and having a steam outlet adjacent said other end wall, tubes located within said boiler shell above the water level in the boiler and extending between said end walls, means for causing hot 10 gases discharged by said flues at one end of the boiler to be conveyed through said tubes to the opposite end of the boiler comprising a chambered casing attached to the end wall of the boiler in register with said tube and 15 flue ends and formed with an offset portion whereby a portion of the end wall between the levels of said tubes and flues is exposed, stay bolts connecting the said exposed end wall portion to the opposite end wall of the 20 boiler, and a baffle arranged within the boiler shell above the water level and below said tubes and steam outlet to provide a steam space above the baffle freely communicating with the steam generating space beneath the baffle only at the end of the boiler 25 remote from said steam outlet.
7. In a horizontal cylindrical boiler, the combination with the boiler shell having a steam outlet and the usual submerged heating flues and other submerged heating surfaces, of a set of tubes located within the boiler shell above the water level therein and below said steam outlet and extending from one end of the boiler to the other, baffle means 30 at the sides of said tubes to prevent water running up the sides of the boiler shell from passing into the spaces between and above said tubes, and means for passing hot gases 35 through said tubes.
